UNITED STATES PATENT OFFICE.

JUDSON L. THOMSON, OF SYRACUSE, NEW YORK.

SHOE-CLASP.

SPECIFICATION forming part of Letters Patent No. 280,583, dated July 3, 1883.

Application filed November 28, 1882. (No model.)

To all whom it may concern:

Be it known that I, JUDSON L. THOMSON, of Syracuse, in the county of Onondaga, in the State of New York, have invented new and useful Improvements in Shoe-Clasps, of which the following, taken in connection with the accompanying drawings, is a full, clear, and exact description.

This invention relates to that class of shoe-clasps in which a tongue hinged on a plate engages with another slotted plate, and is held in two of its operative positions by a spring connected with the plate which carries the said tongue.

15 My present invention consists in certain novel, simple, convenient, and effective means of securing the spring to the plate on which the tongue is hinged, all as hereinafter more fully described and specifically set forth in the 20 claims.

In the annexed drawings, Figure 1 is a plan view of my improved shoe-clasp with the parts interlocked. Fig. 2 is an edge view of the same. Fig. 3 is a detached inverted plan view 25 of the plate to which the tongue is hinged. Fig. 4 is a longitudinal section of said plate. Fig. 5 is a plan view of the tongue-carrying plate with the spring removed; and Fig. 6 is an edge view of the interlocking portion of 30 the tongue and slotted plate, illustrating the means and mode of throwing said plate out of its interlocked position.

Similar letters of reference indicate corresponding parts.

35 A is a metal plate, provided with two or more transverse slots, *a*, for the purpose hereinafter explained, and with an eye for the reception of a rivet or eyelet by which it is to be attached to one of the usual flaps of an 40 overshoe.

B is another metal plate, adapted to be attached in any suitable and well-known manner to the opposite flap or band of the aforesaid shoe. This plate B, I form with two openings, *b b*, and an intermediate cross-bar, *c*, as best seen in Fig. 5 of the drawings, thereby obtaining a rectangular skeleton frame having two parallel side bars, *n n*, which I bend at or near the free end of said plate into semicircular bearings *o* for the pintle *u* of the tongue C, which is thus hinged on said plate. The hinged

end of the tongue C, I form with an eccentric or cam, *d*, as shown in Figs. 2 and 4 of the drawings.

s denotes a spring-plate sprung across the 55 top of the cross-bar *c*, and having its extremities passing through the two openings *b b*, one end of said spring-plate bearing against the under side of the rear or attached end of the plate B, and the opposite end of the spring- 60 plate pressing against the cam *d* of the tongue C, said spring-plate being thus securely attached to the plate B. The under side of the tongue C is provided with a lug or hook, *e*, near the hinged end of said tongue, for the 65 purpose herein presently explained.

In order to allow the plate B to be attached more rigidly and held more closely on the shoe, I provide said plate with additional side bars, *n' n'*, which may be sewed onto the flap or strap 70 of the shoe.

The operation of my improved shoe-clasp is similar to that of others for which I have applied for Letters Patent—*i. e.*, in fastening the clasp the tongue C is inserted through the 75 requisite slot *a* of the plate A and then swung over onto the plate B, thereby drawing the plate A toward and upon the plate B, so as to interlock with the raised portion *o o* thereof. The slot *a* in the plate A, through which the 80 tongue passes, is of sufficient length to allow the raised portions *o o* of the plate B to protrude through said slot, the plate A being thus left with a plain surface uniformly curved to correspond to the contour of the instep of the 85 foot and to invariably lie closely upon the plate with either of the slots *a a* in use. The aforesaid position of the tongue C throws the cam *d* thereof forward on the end of the spring-plate *s* and causes the said spring to press onto 90 the flat side of the cam, as shown in Figs. 2 and 4 of the drawings, thereby imparting a downward pressure on the free end of the tongue and causing the same to securely hold the plate A down upon the plate B. In unfastening the clasp the tongue C is raised and 95 swung toward the plate A. In this movement the lug or hook *e*, which lies under the interlocked end of the plate A, throws said plate off the plate B, as shown in Fig. 6 of the drawings. By swinging the tongue C still further the cam *d* slips rearward on the spring-plate 100

s and throws the free end of the tongue forward into an angle, which allows the plate *A* to be easily removed from the tongue.

Having described my invention, what I claim 5 as new is—

1. In combination with the plate *A*, provided with slots *a*, the plate *B*, formed with the openings *bb* and intermediate cross-bar, *c*, the spring *s*, sprung over the said cross-bar and passing 10 through the slots *bb*, and the tongue *C*, hinged on the plate *B*, and provided with the cam *d*, substantially as described and shown.

2. In combination with the plate *A*, provided with the slots *a*, the plate *B*, having openings 15 *bb* and intermediate cross-bar, *c*, the spring *s*, passing over said cross-bar and into the slots *bb*, and the tongue *C*, hinged on plate *B*, and provided with the cam *d* and throw-off piece *e*, all constructed and combined substantially 20 in the manner described and shown.

3. In combination with the plate *A*, provided with slots *a*, the plate *B*, provided with the spring *s*, bearings *o*, and side bars, *n'*, and the tongue *C*, hinged on plate *B* and provided with 25 the cam *d*, all constructed and combined sub-

stantially in the manner described and shown, for the purpose set forth.

4. The improved shoe-clasp herein described, the same consisting of the plate *B*, formed with the openings *bb*, intermediate cross-bar, *c*, and 30 raised portions *oo*, the spring-plate *s*, passing over said cross-bar and into the slots *bb*, the tongue *C*, hinged on raised parts *oo* and provided with the cam *d*, and the plate *A*, formed with a plain uniformly-curved contour to conform to the instep of the foot, and having slots *aa* of sufficient length to encompass the parts *oo*, all constructed, combined, and operating substantially in the manner described and shown. 35

In testimony whereof I have hereunto signed my name and affixed my seal in the presence of two attesting witnesses, at Syracuse, in the county of Onondaga, in the State of New York, this 1st day of November, 1882.

JUDSON L. THOMSON. [L. S.]
